UNITED STATES PATENT OFFICE.

RAYMOND D. SMITH, OF MILTON, MASSACHUSETTS, ASSIGNOR TO SHAWMUT MACHINE WORKS, INC., OF BOSTON, MASSACHUSETTS, A CORPORATION OF MAINE.

DELAYED CUT-OFF FOR INCANDESCENT GAS-LAMPS.

1,383,574.

Specification of Letters Patent.

Patented July 5, 1921.

Application filed August 2, 1916, Serial No. 112,828. Renewed October 4, 1920. Serial No. 414,649.

To all whom it may concern:

Be it known that I, RAYMOND D. SMITH, a citizen of the United States, residing at Milton, in the county of Norfolk and State 5 of Massachusetts, have invented certain new and useful Improvements in Delayed Cut-Offs for Incandescent Gas-Lamps, of which the following is a specification.

My present invention relates to delayed 10 cut-offs for illuminating gas burners of the Bunsen type wherein the light is produced by the incandescence of a mantle, or non-combustible fabric structure, suspended from above, and directly over, the upper, open 15 end of a vertical mixing chamber for the gas and air of the Bunsen burner; the lower portion of said mantle overhanging and surrounding the upper portion of said mixing chamber; and the entire mantle structure 20 being contained within a chimney chamber, substantially closed at the bottom and open at the top, with the usual air vents in the wall of the chimney.

The principal object of the invention is 25 to provide in self-contained combination with an illuminating gas burner of the type above described, a valve for controlling the supply of gas to such burner, and manually operable automatic instrumentalities for 30 said valve, whereby one manual actuation of said instrumentalities will open the valve to deliver gas continuously to the incandescent mantle burner (which may then be lighted as usual and remain in operation 35 for an indefinite period of time) and whereby a subsequent manual actuation of said instrumentalities will render same operative to effect delayed, lamp-extinguishing closure 40 of the valve. The time interval before such closure is then controlled by thermostatic means subject to the heat of a normally inactive, auxiliary burner to which gas is supplied by the above mentioned subsequent actuation, which auxiliary burner is there- 45 upon ignited by the heat from the main burner and thermally energizes the thermostat, thus releasing tensioned actuating means and causing thereby a quick and positive closure of the valve and complete exting- 50 uishment of both the main and auxiliary burners.

A further object of my invention is to provide, in such an illuminating burner, simple and efficient means for causing re-

liable automatic ignition of the auxiliary 55 burner from the heat of the main mantle burner, without impairment of the mantle (which latter is very frail and brittle) and without introducing new elements into the chimney inclosed space surrounding the 60 mantle.

Other specific details and objects of my invention will appear from the drawings, description and claims hereof.

In the drawings:—Figure 1 is a rear ele- 65 vation, partly in section, of the entire burner and valve structure; Fig. 2 is a plan view of the valve mechanism and of certain auxiliary burner parts, the upper mantle structure being omitted and certain parts broken 70 away to more clearly show the valve mechanism; Fig. 3 is a front elevation of the valve controlling mechanism, showing the position of parts after automatic closure of the valve; Fig. 4 is an enlarged partial sec- 75 tion taken on the plane 4—4 in Fig. 2 showing the arrangement of valve ports and their relative positions during normal operation of the main illuminating burner; Fig. 5 is a section similar to Fig. 4, but showing a 80 different relation of ports; Fig. 6 shows the relation of valve ports when the light has been extinguished; Fig. 7 is a partial eleva- 85 tion looking at the right of Fig. 1; Fig. 8 is a view similar to Fig. 3 showing the position of the valve controlling mechanism after manual actuation of extinguishing means and before automatic closure of the valve or while the thermostat is heating.

Similar and corresponding parts are in- 90 dicated throughout the drawings and designated in the following description by the same numerals.

Referring to Fig. 1, particularly, the illuminating mantle appears at 1, and is of 95 the conventional type suspended by its top between the legs of a staple-shaped, single wire support 2 which legs at their bottom are fixed to a cylindrical metal shell base 3 extending into the open bottom of the 100 mantle sufficiently to steady the latter and externally mounted on the open and enlarged upper portion 4 of the upright, combined supporting stem and mixing chamber 5 for the gas and air of the main Bunsen 105 burner. At the bottom of the mixing chamber 5, is shown the usual gas injector and air intake construction wherein adjustment

of the gas supply may be had by means of the rotary sliding disk 6. This disk is perforated and pivotally clamped in gas tight surface contact with a flat stationary seat 5 7, similarly perforated. The rotary sliding disk 6 has an extension 8, engaged by a slot in the rotary hood 9, so that adjustment of the gas supply may be had by turning the hood 9. The hood 9 has in its bottom surface 10 numerous perforations 10, for the entrance of air to the mixing chamber 5, such Bunsen gas burner construction being well known in the art.

The combined supporting stem and mixing chamber 5 terminates below the Bunsen gas injector construction in an internally threaded portion 11 and is mounted at this portion upon a valve block 12 which latter, at its bottom, has an internally threaded portion 14, by means of which the entire structure may be mounted upon the usual gas bracket or chandelier.

The enlarged upper portion 4 of the mixing chamber 5 is removable from the latter 25 and is structurally integral with a punched metal, circular bracket 13 having a floor portion which may be formed by a separate annularly shaped disk such as 13^a spun into the bracket 13 and serving thereby to reinforce the same, to check excessive upward air draft past the mantle and to prevent broken particles of the mantle, etc., from falling out of the combustion chamber. The bracket 13 is arranged to receive and hold 35 a cylindrical glass chimney 16 having openings 17 in its wall.

The valve block contains the usual rotary tapered valve plug 15 whose axis lies transverse of the vertical main gas passage 18, 40 through said block, and which, when rotatively actuated by mechanism to be described hereinafter, controls the supply of gas to both the main burner stem 5 and to a small auxiliary heating burner 21 that 45 extends upwardly from a bracket extension 22, of the valve block. It should be carefully noted that the upper orifice of the auxiliary heater burner 21 is at a substantially higher level than the perforated bottom portion 50 of the air intake-opening hood 9 of the main Bunsen burner and that said hood effectively separates the said air openings from the burner 21. Were the air intake-opening not shielded from the flame of the 55 auxiliary burner, the latter would ignite the gas at its point of injection into the main Bunsen burner mixing chamber, and thereby impair the operation of the main illuminating burner. Adjustment of the supply of 60 gas to the burner 21 may be had by the screw 23.

In the other bracket extension 24 of the valve block 12, an upwardly slanting gas port 27 is shown leading from the main gas 65 passage, below the valve plug 15, to the base

of an upright tube 25 which tube at its top is inclosed by a larger clay tube 28, the upper end of the latter being adjacent to the mantle. Gas supply to this tube may be controlled by the adjusting screw 26. It 70 will be evident that when ignited, the small flame 29 at the top of the tube (commonly called a pilot light) will remain constantly burning independent of the valve 15 and that this flame is so situated as to ignite the main mantle burner whenever gas is supplied to the latter.

Referring particularly to Figs. 2, 3 and 8, I shall now describe the mechanism by which the movement of the valve plug 15 is controlled. Manual control of this mechanism is afforded by the chains 65 and 68. A downward pull on chain 68 in Fig. 3 first swings the spring actuated latch lever 66 to the broken line position, thus disengaging 85 it from the locking projection 78 of the vertical, circular supporting plate 31 which is fixed to the valve block. The latch lever 66 is pivoted to the end of a double-ended control lever 35 which carries the chain 65 at 90 its other end and which is loosely mounted on a stem extension 30 of the valve plug 15. Further pull on the chain 68 will therefore swing the control lever 35 to its position indicated by broken lines in Fig. 3, where 95 it will be stopped by engagement with another projection 54 of the supporting plate 31. During this movement, the valve plug has been positively rotated a corresponding amount by engagement of the control lever 100 35 with a rearwardly bent extension 37 of the dog member 36, the latter being fast to the end of the valve stem 30 and normally held in such engagement with the control lever 35 by a spring 38, one end of which 105 is hooked under the edge of control lever 35 and the other end of which is hooked over the extension 37. Control chain 65 may now be pulled downwardly which will swing the control lever 35 in the reverse direction 110 until the spring latch lever 66 automatically locks said control lever in the position shown in Figs. 3 and 8. But from Fig. 8 it will be seen that during the latter movement, the dog member 36 has been intercepted in an 115 intermediate position and that it is held in this position against the tension of spring 38 by a spur shaped projection 52 carried fast to the inner surface of the curved bimetallic thermostat 53.

The thermostat 53 is mounted at one end to the projection 54 of the supporting plate 31 and is clamped thereto in surface contact with the base of an upwardly extending heater member 56 by screws 55, 55. The 125 heater member 56 terminates in a hooded portion 57 that is perforated at its top and is positioned directly over the auxiliary burner 21.

Directly above this hooded terminal of the 130

heater member is an open ignition tube 32 supported by and preferably flush at its top with the hereinbefore mentioned annular floor portion 13^a of the chimney-holder 13 and opening therethrough into the bottom of the main mantle chimney chamber. The lower end of this ignition tube encompasses the perforated top of the heater hood but leaves a free passage for air into said tube 10 around the exterior of the hood. In the construction illustrated two means are provided for maintaining the necessary vertical alignment of the ignition tube 32 above the flame orifice of heater burner 21. One of 15 these is the vertical overlapping at the bottom of said tube and the top of heater hood 57. Or in case these two parts should not so overlap the protrusion of pilot tube 25 through the chimney holder 13 and its annular floor portion 13^a, will maintain the designed rotative position of the removable holder 13 on the Bunsen stem 5. Such use 20 for the pilot tube 25 constitutes a new and useful function thereof in the arrangement 25 herein disclosed. Gas rising from the auxiliary burner 21 and through the opening at the top of the heater hood is guided upwardly through the chimney tube 32 into the chimney inclosed space surrounding the 30 mantle, and upon igniting from the heat of the latter, flares back through said tube and subsequently burns with a blue flame at the top of the burner 21 only, and under the hood 57 as shown in Fig. 8. A loose stationary roller 61 is mounted on a stud projecting from the support plate 31 and engages the inner surface of the thermostat to help the thermostat bear the load of the tensioned dog member 36. This dog member 35 engages the thermostat spur 52 by means of a spring actuated latch 46, pivoted to the dog member at 47, and capable of yielding in one direction only, namely counter clockwise in Fig. 8, or when passing the spur 52 by clock-wise rotation of the dog member 36. A casing 33 is provided for the valve mechanism.

Having thus described the controlling mechanism, I shall now explain the operation 50 of the complete burner and valve arrangement, after which I shall point out what constitutes the novel features of my invention in the appended claims.

Starting from the position of parts as 55 shown in Fig. 1 (and by broken lines in Fig. 3) where the valve ports are related as in Fig. 4 and where the main mantle burner is lighted and adapted for continuous operation,—when it be desired to extinguish the 60 light, control chain 65 is pulled downwardly which moves the parts to the position indicated in Fig. 8, where the valve ports are related as shown in Fig. 5. It will be seen that the small port 19 in the valve plug now 65 registers with the corresponding port 20

leading to the auxiliary burner 21 in the valve block, and that gas is thereby supplied to said auxiliary burner which then ignites, as heretofore described, from the heat of the main mantle burner, the supply of gas to 70 which latter burner has been substantially unaltered by movement of the valve plug. The flame of the auxiliary burner now plays against the hooded terminal 57 of the heater 75 56 as shown in Fig. 8, which latter member 75 conducts heat from said flame to the thermostat. The thermostat upon being thus heated, straightens, or bends generally outwardly, assuming the broken line position indicated in Fig. 8 after a certain time interval, whereupon the spur 52 releases the dog member 36, and the latter is immediately impelled by the spring 38 to the position shown in Fig. 3, where the relation of valve ports is as shown in Fig. 6, and all 80 gas supply to both the auxiliary heater burner and to the main mantle burner has been cut off. The pilot flame 29, however, remains burning and when gas is again supplied to the main mantle burner, ignites the 85 latter.

The valve may be opened again at will for supplying gas to the main mantle burner, by pulling downwardly on chain 68. This restores all parts to the original positions 90 shown in Figs. 1 and 4 as before explained. It should be noted that in this position, no 95 gas is supplied to the auxiliary burner 21 and that the main mantle is adapted to remain in operation for an indefinite period of 100 time.

It will be apparent to those skilled in the art that the precise embodiment of my invention herein chosen for illustrative purposes may be still further varied in many 105 respects without departing from the essential governing organization contained therein, and constituting the real invention.

Having thus broadly described the construction and operation of a preferred embodiment of my present invention, what I claim as new is:

1. In an upright mantle gas lamp and controlling valve arrangement embodying a Bunsen burner stem and automatic agencies 115 for governing the valve, said agencies including an auxiliary heater burner arranged laterally of said Bunsen stem, in combination; a mantle-carrying lamp structure removably mounted on the Bunsen stem above 120 said auxiliary burner and comprising a transparent chimney and holder therefor, the latter having an annular floor portion at the base of said chimney separating the mantle from said auxiliary heater burner; 125 and an open-ended gas-directive tube opening through and protruding downwardly from the floor portion of the removable chimney holder and carried thereby in a position to terminate at its lower end di- 130

rectly above the flame orifice of said auxiliary burner.

2. In an upright mantle gas lamp and controlling valve arrangement embodying a Bunsen burner stem and automatic agencies for governing the valve, said agencies including an auxiliary heater burner arranged laterally of said Bunsen stem, in combination; a mantle-carrying lamp structure removably mounted on said Bunsen stem above said auxiliary burner and comprising a transparent chimney and holder therefor, the latter having an annular floor portion between said Bunsen stem and the base of said chimney separating said auxiliary burner from the mantle; and an unconstricted gas directive tube fixedly secured to and substantially

flush at its upper open end with said floor portion of said chimney holder and extending downwardly therefrom to terminate at 20 its open lower end directly above the flame orifice of said auxiliary burner, together with means to maintain a constant rotative position of said lamp structure on said Bunsen stem thereby to insure the true alinement of said gas directive tube above the auxiliary burner.

Signed in Boston, Massachusetts, this first day of August, 1916.

RAYMOND D. SMITH.
